UNITED STATES PATENT OFFICE

2,230,529

TONSILLOTOME

Oscar C. Daniels, New Bern, N. C.

Application October 7, 1939, Serial No. 298,503

2 Claims. (Cl. 128—309)

This invention relates to improvements in surgical instruments, its particular purpose being for severing and removing tonsils and the like. Reference is made to the patent to O. C. Daniels, 5 1,466,581 of August 28, 1923, on which the improvement is based. It is thought unnecessary to describe the advantages of the known instrument at length because that was done in the foregoing patent. It is desired to state, however, that 10 in the use of the patented instrument it was found that the cutting blade is subject to a limited jamming, thereby restricting the freedom of movement that is desired, also that the necessary looseness between the spindle and sleeve has 15 the fault of rendering the instrument slightly unsteady at times. The necessity for said looseness comes out of a requirement for the easy disassembly of the parts preparatory to sterilization, but this same looseness has the fault of 20 setting up some rattling when the parts are reassembled preparatory for use.

With this preamble in mind, the objects of the invention are as follow:

First, to provide a surgical instrument of the 25 character stated wherein the utmost freedom in the sliding movement of the blade is insured by the provision of at least one stud or equivalent spacing means between the frame and cover member, thereby to enable the operator to manipulate the instrument smoothly and easily and 30 without unduly jarring the patient.

Second, to provide a brake between the spindle and sleeve so as to frictionally hold the sleeve in reference to the spindle while making preliminary adjustments of the thumb wheel for the 35 initial setting of the cutting blade.

Other objects and advantages will appear in the following specification, reference being had to the accompanying drawing, in which:

40 Figure 1 is a side elevation of a tonsillotome embodying the improvements.

Figure 2 is a longitudinal section of a portion of the instrument, particularly illustrating the spacer stud and brake.

45 Figure 3 is a cross section taken on the line 3—3 of Fig. 2.

Figure 4 is a cross section taken on the line 4—4 of Fig. 2.

50 Figure 5 is an inverted plan view of the cover member which carries the spacer stud.

Figure 6 is a plan view of a portion of the blade.

55 Figure 7 is a plan view of the cover member, particularly illustrating the brake spring on the spindle.

Figure 8 is a detail plan view of the cutting end of the instrument.

Figure 9 is a cross section taken on the line 9—9 of Figure 8.

Figure 10 is a longitudinal section taken on the 5 line 10—10 of Fig. 8.

For the purpose of a general understanding of the patented instrument, the structure of the latter is described briefly before pointing out the improvements. A frame 1 provided with a handle 2 has a widened portion 3 at one end. The upper face 4 of the frame is flat throughout its length. The widened portion 3 has an aperture 5 to receive the tissue to be cut off. Said portion has a marginal flange 6 which serves the purpose of a 15 guide.

At a place adjacent to the handle 2 the frame 1 has an integral upstanding guide flange 8. This is substantially U-shaped in cross section (Fig. 3). A blade 9 is adapted to slide upon the flat 20 upper face 4. This blade has a widened portion 10 (Figure 8) which is sharpened at its front end to provide a cutting edge 11. The end of the blade opposite to the widened portion is bent upwardly at 12, the resulting flange being recessed 25 at 13 (Fig. 6).

A cover member 15 is seated upon the blade 9 to assist in its retention. Said member has a widened end portion 16 (Fig. 8) to match the widened portion 10 of the blade. The edge 17 30 of the widened portion 16 is smooth and is provided with lateral flanges 18. A boss 19 occurs on the cover member 15 at that end opposite to the widened portion 16. A spindle 21 projects from the boss 19. The spindle is integral with 35 the boss and its free end is externally threaded as shown in Fig. 2. A sleeve 22 is mounted for rotation on the spindle 21 and is provided with a stud 23 which is adapted to move in a cam opening 24 in the flange 8 so as to drive the 40 widened portion 16 forwardly at a period in the operation of the instrument.

The sleeve 22 is externally screw threaded at 45 25. A nut 26 screwed onto the threads of the spindle 21 provides a back stop for the sleeve 22, 45 the boss 19 providing the companion front stop.

A thumb wheel 27 is screwed onto the threads 25 of the sleeve 22. It has a grooved collar 28 with which the flange 12 is loosely connected by virtue of the recess 13 of the latter. A wing nut 50 29 is fixedly secured to the outer terminal of the sleeve 22 adjacent to the thread course 25.

An opening 30 in the frame 1 is undercut to receive the head 37 of a spring clip 35. The shank 36 of this spring clip is insertible through 55

slots 31 and 34 respectively in the blade 9 and cover member 15 prior to the introduction of the head 37 into the opening 30. This is done with the spring clip 35 at a position 90 degrees to one side of the ultimate position in Fig. 1. The turning of the spring clip to that position locks the shank 36 upon the frame 1. The blade 9 and cover member 15 have an interengaging stud and slot connection not necessarily detailed herein, this ending the description of the known structure.

The improvement to the foregoing instrument involves several features, each of which is a contribution toward the better working of the device. A spacer stud 38 (Fig. 2) insures the utmost freedom of sliding movement of the blade 9 because said stud is made sufficiently deeper than the blade 9 is thick to provide a noticeable clearance 38 above and below said blade. Actually the blade will ride the face 4, but it is conceivable that the blade may move up and down in the space provided for it, this facility being the occasion for making particular reference to the clearances 38. The stud 38 may be attached either to the frame 1 or to the cover member 15. By preference it is a part of the cover member 15, but in either case it occupies a slot 39 in the blade, said slot being specifically provided for the stud. In order to make sure that the blade 9 will slide as freely at its widened portion 10 as elsewhere along its length, the marginal flange 6 (Fig. 8) is provided with a separate groove 40 (Fig. 9) to which the side edges of the widened portion 16 of the cover member 15 are confined. The widened portion 10 of the blade 9 rides in individual grooves 41 to which the side edges of said widened portion are confined. The blade 9 is thus kept free from the cover member 15, and it is this spacing that insures the freedom of sliding movement of the cutting blade to which much importance is herein attached.

In practice there have been instances when there was a tendency for the blade 9 to retard a little during the operation. Such an occurrence is attended by a slight jarring of the patient due to an extra effort on the part of the surgeon to manipulate the blade for the purpose of overcoming the resistance. This fault is avoided by mounting the blade 9 independently of the cover member 15 and in a sense also independently of the frame 1. Instead of grouping the two widened portions 10, 16, in one slot, each is confined to its own slot in the marginal flange 6, with the result already stated.

The second feature which characterizes the improvement is the use of a spring 42 (Fig. 2) as a brake between the spindle 21 and sleeve 22. This is preferably a leaf spring but not necessarily so. In the event of using a leaf spring rivets 43 or their equivalents are employed to rigidly set one end of the spring in a depression 44 in the stem 21. The spring 42 is fairly stiff, and inasmuch as its tension is outward it will bear on the bore in the sleeve 22, producing a desired factor of resistance.

Instead of utilizing the nut 26 as a means for clamping the sleeve 22 and thus hold said sleeve against rotation of the spindle 21, said nut 26 is now used as a back stop between which and the boss 19 the sleeve 22 is perpetually turnably mounted. In other words, the sleeve 22 is herein adapted always to be freely turnable between the front and back stops 19, 26, but in order to stabilize the sleeve use is made

of the brake spring 42 to steady the sleeve in respect to the spindle 21 while making preliminary adjustments of the thumb wheel 27.

Such adjustments are made when setting the cutting blade 9 at the beginning of an operation. At such a time it is most desirable to have every element to function properly and without hindrances. The surgeon can give the wheel 27 one or two spins, thereby to slide the blade 9 backward or forward and at that time it is desirable not to have the sleeve 22 turn.

This could be prevented by holding the wing nut 29 with the fingers of the other hand, but the use of the spring 42 does away with that necessity. The turning of the thumb wheel 27 can be accomplished without disturbing the position of the sleeve 22 which might occur because of the frictional engagement of the threads, but the spring 42 holds the sleeve 22 with sufficient tightness in respect to the non-revolvable spindle 21 that the spinning of the thumb wheel 27 can be accomplished without having to hold the wing nut 29.

Reverting to the free sliding of the blade 9 to the insurance of which end the grooves 40, 41, 25 are provided (Fig. 9) due attention has been paid to the possibility of some portion of membranous material catching in the space between the blade 9 and the cover member 15. Said space, now designated 45 in Fig. 9, is slight, being only of a depth equal to the thickness of the rib 46 which divides the grooves, but even this slight space if left unguarded might cause the disorder just mentioned.

As a preventative the widened portion 16 is made extra thick at 47 (Fig. 10). That is to say, the extremity of the portion 16 is made with an extra thickness underneath, substantially as suggested by the outline 47 in Fig. 8. This extra thickness brings the material of the cover member very close to the top of the blade 9. It thus functions as a closure for the space 45 and also as a bearing member for the blade. If there should be any tendency of the latter to deflect upwardly the thickened portion 47 would serve as a stop.

Briefly stating the operation, the cover member 15 and blade 9 are retracted by pulling back on the wing nut 29. This can be done only after the stud 23 has registered with the passage 50 beneath the guide flange 8. The widened portions 10, 16, then clear the aperture 5. The instrument is brought into position so that the tissue can be emplaced in said aperture. The nut 26 is then pushed upon by the thumb of the hand that holds the instrument until the tissue is pressed between the smooth edge 17 and the closed end of the marginal flange 6.

This portion of the operation is completed by turning the wing nut 29 whereupon the stud 23 rides into the cam opening 24 and thus secures the widened portion 16 in its clamping or squeezing position. The thumb wheel 27 is now turned until the cutting edge 11 appears beyond a slit in the rounded end of the flange 6. This denotes the severance of the tissue and the severed parts are then removed.

I claim:

1. In a surgical instrument comprising a frame having two sets of grooves with an intervening rib, a cutting blade and a cover member superimposed on the blade, said blade and cover member being individually slidably in the respective sets of grooves, said rib spacing the cover member from the frame at the cutting end of the

blade thus to insure the free sliding of the blade independently of the cover member; in combination, means for further spacing the cover member from the frame consisting of a spacer stud upstanding in reference to the frame and higher than the blade is thick, said blade having a slot occupied by the stud.

2. In a surgical instrument having a frame carrying a blade and a cover member for the blade, a spindle extending integrally from the cover member and having a depression in its

cylindrical wall, a sleeve revoluble on the spindle, said sleeve having a threaded portion, a thumb wheel having a connection with the blade and being turnable on the threads to reciprocate the blade, and a leaf spring occupying the depression, therefore being interposed between the spindle and sleeve to brake the sleeve and check its tendency to turn when turning the thumb wheel. 5

OSCAR C. DANIELS. 10
